FIRING HEAD ASSEMBLY FOR FUEL BURNERS

Ralph W. De Lancey, Yalesville, Conn., assignor to The Miller Company, Meriden, Conn., a corporation of Connecticut

Application April 14, 1951, Serial No. 221,041

8 Claims. (Cl. 158—76)

1

This invention relates to a firing head assembly for fuel burners, and more particularly to a firing head for gun burners of the type in which the fuel is pumped under pressure to a nozzle and there atomized in the form of a mist or spray and mixed with a blast of air supplied by a blower, the resulting fuel-air mixture being discharged into the combustion chamber of the furnace where it is burned. Due to imperfections in the orifice of the fuel nozzle, the pattern of dispersed or atomized fuel is often irregular, that is, greater amounts of fuel are discharged in some directions than in others. These imperfections may be occasioned by slight mechanical inaccuracies inherent in the method of manufacturing the nozzle, or they may arise from the formation of a slight, tenacious film deposited in the orifice during use of the burner. In either case, such imperfections cause the flame produced by the burner to have a "tail" or "tails" which jut out from the main body of the flame. This leads to improper combustion and consequently lowers the efficiency of the burner apparatus.

It is a purpose of the present invention to provide a firing head construction which will permit adjustment to be made whereby the effect of these irregularities may be largely, if not wholly, compensated for. Furthermore, by means of the novel firing head construction hereinafter described, the aforesaid compensation for flame irregularities may be accomplished while the burner is in actual operation so that the effect of the adjustment made is immediately observable. Heretofore it has been necessary where flame pattern irregularities of the type here in question have occurred to shut off the burner equipment and to disassemble it sufficiently to permit withdrawal of the firing head assembly from the air blast tube or duct so that the nozzle can be cleaned or otherwise adjusted or replaced. The equipment must then of course be reassembled and started up again in order to determine whether the difficulty has been cured. It will be obvious from the foregoing that it is practically impossible for a service man to determine in advance whether or not he is accomplishing the desired result, and he must therefore resort to repeated disassembly, reassembly and operation of the equipment. It is not at all an uncommon experience in actual practice to find that considerably more than half of any average group of nozzles picked at random, all of the same make and model, will produce a tail or tails in the flame when installed in a burner. As explained above, these tails are caused by very slight, sometimes

imperceptible, imperfections in the nozzle orifice which cause or at least allow the discharge of an excess amount of oil in a particular direction, with the result that not all of the oil in that tail is properly mixed with air and burned. Where these tails extend downwardly toward the bottom of the combustion chamber, they are deflected by the walls of the chamber and are curled back toward the main body of the flame where further mixing of the excess fuel with additional air supplied by the blower can then occur. Under such circumstances combustion is more nearly complete and the imperfections are of little importance. Where, however, the tail is directed upwardly towards the top or sides of the combustion chamber, there is little or no opportunity for this re-mixing to occur, and the excess fuel in the tail is carried off into the flue of the furnace by the draft produced without being burned. The usual method of mounting the spray nozzle in a burner is simply to screw it into a nozzle adapter on the end of the fuel supply line leading from the pump, both the adapter and fuel line being held rigidly in substantially fixed position in the burner blast tube. Since the nozzle must be screwed tightly into the adapter to avoid leakage of fuel at that point and cannot as a practical matter be rotatively adjusted with respect to the rest of the firing head assembly, little or no control of the direction can be accomplished in which a tail, if present on the flame, extends in the combustion chamber. In most prior burners, therefore, it is wholly a matter of chance in what direction the tail shall extend and the solution to the problem has been to disassemble the burner and replace the nozzle with a different one until one is found which gives a satisfactory flame pattern. And even in the one or two instances in which attempt has been made in the prior art to allow for rotative adjustment, only limited adjustment has been achieved, and this by rotating the entire firing head assembly. Not only does this require that the ignition electrodes be mounted independently of the rest of the firing head (commercial codes require these to be horizontally opposed) but it also introduces further problems of disturbing the air distribution because of rotation of the deflector vanes.

With the use of the firing head here disclosed, the flame produced by the burner may be bodily turned about its axis any desired amount while the burner is operating, in order to position a tail at or near the floor of the combustion chamber, and this is accomplished without in any way dis-

turbing the ignition electrodes or air deflector vanes.

A specific embodiment of the invention is illustrated in the accompanying drawings and described in detail hereinafter. The drawing and description are, of course, merely illustrative and various modifications can be made as will be apparent.

In the drawings

Fig. 1 is a diagrammatic illustration in side elevation of a burner firing into a combustion chamber, the flame produced having a typically irregular pattern;

Fig. 2 is an illustration of the same burner shown in Fig. 1, adjustment having been made as provided by the present disclosure to compensate for the irregular flame pattern;

Fig. 3 is a side elevational view, partly in section and partly broken away, of a gun burner air duct having a firing head assembly constructed in accordance with the invention; and

Fig. 4 is a fragmentary view in plan looking from below, of the forward portion of the firing head assembly shown in Fig. 3.

Fig. 1 illustrates a typical case in which a burner 10 is employed in conjunction with a furnace having walls 11 defining a combustion chamber 12. In this instance the flame produced by the burner assumes an irregular pattern, the main body of the flame being indicated at 13 and having a tail 14 which extends upwardly toward the top of the combustion chamber 12. Under these conditions, there is some waste of fuel because an appreciable amount of the potentially combustible volatile products present in the tail 14 passes out through the flue of the furnace in an unburned or only partially burned condition. The flame pattern here illustrated is, of course, the extreme case, in that the tail is directed substantially straight up in the combustion chamber, but a similar loss occurs whenever the tail, if present, is located at any point other than substantially at or near the bottom of the main body 13 of the flame. The ideal situation, of course, is one in which the flame pattern is perfectly symmetrical in all directions, but as explained above this is not obtained in actual practice in most cases.

Fig. 2, on the other hand, shows what occurs when the tail 14 is positioned on the under side of the main body of the flame. In this instance, the tail strikes the floor, or the walls adjacent the floor, of the furnace and is directed back toward the main body 13 of the flame. Where this occurs, the unburned volatile products carried by the tail 14 are mixed with additional air supplied by the burner 10 and are burned in the main body of the burner flame. Not only does this increase the efficiency of the burner by more completely burning the fuel, but it also reduces the formation of soot which would otherwise be deposited upon the heat exchange surfaces of the furnace, thereby lowering the heat transfer efficiency of those surfaces.

A firing head assembly is shown in Figs. 3 and 4 which will permit a service man to turn the body of the flame about its axis as it issues from the burner blast tube. In Fig. 3, the portions of burner 10 shown include the rear of the blower housing 15, the forward part of the blast tube or duct 16 and the enclosed firing head assembly indicated generally at 17. The latter extends from a point adjacent the discharge end of duct 16 back through the rear wall 15a of the blower housing. Firing head assembly 17 includes a cen-

tral fuel pipe or conduit 18 which is carried within a loosely fitting sleeve 19 which, as will more fully hereinafter appear, is suitably held against turning movement about its axis. The conduit is threaded at its rear or fuel-receiving end, and an internally and externally threaded nipple 20 is screwed on to that end of the conduit. Nipple 20 receives a gland nut 21 which serves to connect the flared end of the fuel supply pipe 22 to the fuel conduit 18. The forward end of conduit 18 is also threaded and is received within a nozzle adapter 23 having a passage 24 which extends axially through the adapter. At its forward end, the adapter carries a spray nozzle 25 provided with the usual filter 26 through which the fuel oil passes in going to the very fine discharge orifice of the nozzle. The firing head assembly is also provided at its forward end, adjacent the nozzle, with stationary air deflector or swirler vanes 27 which are used to impart a turbulence to the air as it is emitted from the blast tube in order to effect a better mixing of air with the atomized fuel. In this instance the deflector vanes 27 are formed by radially slitting an annular disc 25 or flange forming a skirt at one end of a tubular shell or hub 28 and then bending the blade members thus formed out of their original plane into non-coincident, substantially parallel planes. The over-all diameter of the air deflector corresponds to the internal diameter of duct 16 so that the tips of blades 27 contact the duct circumferentially and thus center the deflector in the duct. Shell 28 is made fast to a second tubular member 29 fitting therewithin and having, at its rear end, small lugs 30 which serve to hold the adapter 23 and nozzle 25 in spaced coaxial relation to member 29. As seen in Fig. 3, the air deflector just described is provided with a bridge member 31 secured to the under side of shell 29 at its rear end. Bridge 31 extends rearwardly in cantilever fashion from the deflector assembly and is connected to a yoke 32 by means of screw 33 to support the yoke in the duct 16. Yoke 32 is apertured centrally to receive the forward end of sleeve 19, as well as to allow fuel conduit 18 to pass therethrough. A setscrew 34 located in the same hole as screw 33 serves to lock the yoke 32 to the forward end of sleeve 19, but conduit 18 is left free for rotation within the sleeve. In this manner conduit 18, nozzle adapter 23 and nozzle 25 are free for rotational movement within sleeve 19 independently of the air deflector assembly, and at the same time are supported within the blast tube 16 by the latter means. Yoke 32 also carries the rear ends of the ignition electrodes 37 and their porcelain insulators 38 to dispose them horizontally on opposite sides of the nozzle and nozzle adapter in conventional manner, the electrodes and insulators being supported adjacent their forward ends by the deflector in passing through holes provided therein for that purpose.

At the fuel-receiving end of conduit 18, a collar or bushing 35 is welded or otherwise suitably secured to sleeve 19. This collar fits closely within an aperture 36 provided in the rear wall 15a of the blower housing so that the firing head assembly is thus supported adjacent its fuel-receiving end by the wall of the blower housing. As here shown, collar 35 has a locating key or lug 35a secured to it which fits into a corresponding slot or keyway 15b opening into aperture 36 in wall 15a. This serves to angularly position the air deflector and electrode assembly of the firing head within duct 16 and serves also to prevent

turning of this assembly with rotative angular adjustment of the nozzle 25 now to be described. In order to rotatively adjust the nozzle so as to put any tail on the flame produced thereby at or near the bottom of the main body of the flame, it is merely necessary in the construction here shown to partially uncouple gland nut 21 from nipple 20 in order to permit doing this. Even though the burner is in operation and fuel is being supplied to the fuel pipe 22 under considerable pressure, sufficient uncoupling can be accomplished without letting oil leak out at this point to permit the conical seat provided by the flared end of tube 22 to turn on the mating surface of the nipple 20. With the coupling connection thus loosened, proper application of a wrench to the head of nipple 20 whereby to turn the whole unit, consisting of said nipple, fuel conduit 18, adapter 23 and nozzle 25, through the necessary angular distance to accomplish the desired adjustment. Since, in this adjusting movement, the fuel conduit turns within stationary sleeve 19 while the nozzle adapter turns within member 29 which is fast with shell 28, said adjusting movement causes no rotation or turning movement of the air deflector assembly and the electrodes carried thereby. Furthermore, no strain or twisting is imparted to the fuel line 22 since the conical tip of nipple 20 simply turns within the flared mating end of pipe 22. The service man can thus adjust the angular position of the nozzle until the desired positioning of the flame is obtained. When this has been done, the coupling connection can again be tightened up by turning gland nut 21. The construction shown thus permits angular rotative adjustment of the nozzle without in any manner disturbing the air deflector means and, equally as important, without disturbing the ignition electrodes.

As here shown, sleeve 19 extends the full distance between the shoulders of nipple 20 and the rear end of the nozzle adapter 23. This construction thus prevents any axial shifting of the nozzle with respect to the position of the deflector vanes 27, which is desirable for many applications. If desired, of course, the construction can be such that axial adjustment can be made both in the positioning of the entire firing head assembly with respect to the mouth 39 of the blast tube 16 and also in the positioning of the nozzle 25 with respect to the air deflector vanes 27. Similarly, while it is convenient from a manufacturing standpoint to have sleeve 19 in bearing contact with conduit 18 throughout the length of the sleeve, this is not essential as will be readily appreciated.

The principles of the present invention are applicable equally to burners producing a substantially solid body of flame such as that diagrammatically illustrated in Figs. 1 and 2, as well as to burners producing a hollow conical flame. Both types are subject to the presence of unwanted tails on the flame.

The term spray nozzle assembly as used herein refers not only to the terminal member having the fine orifice from which the oil spray actually emerges at the mouth of the blast tube, but it also includes an adapter member, where one is present, connecting the terminal nozzle member to the fuel conduit.

What is claimed is:

1. A firing head assembly for fuel burners of the gun type having a tubular air blast duct adapted for connection to a blower, which assembly is adapted and arranged to be positioned

in said duct and which comprises a fuel conduit having fuel-receiving and discharging ends, coupling means at the fuel-receiving end of said conduit for connecting the latter to a source of fuel, nozzle means connected to the fuel-discharging end, a sleeve surrounding said conduit and in bearing contact therewith to permit rotatively angular adjustment of said conduit therein, supporting means for positioning said assembly within said duct, said supporting means fixedly engaging said sleeve to prevent rotatively angular movement of the latter with such movement of said conduit, and ignition means so carried operatively adjacent said nozzle means by said supporting means as to prevent said ignition means from participating in said angular adjustment.

2. A firing head assembly for fuel burners of the gun type having a tubular air blast duct adapted for connection to a blower, said assembly being adapted and arranged to be positioned substantially axially in said duct and comprising a fuel conduit having fuel-receiving and discharging ends, a spray nozzle assembly secured to the discharge end of said conduit, air deflecting means surrounding said nozzle assembly in concentrically spaced relation thereto, a sleeve surrounding said conduit and in bearing contact therewith to permit rotatively angular adjustment of the latter therein, a yoke secured to said sleeve, said yoke being supported from said deflector means whereby said sleeve is positioned substantially axially of said duct, and ignition means carried partly by said yoke and partly by said air deflecting means, said conduit being free of said yoke to permit rotatively angular adjustment of said conduit within said sleeve independently of said yoke and air deflector means.

3. A firing head assembly for fuel burners of the gun type having a tubular air blast duct adapted for connection to a blower, said assembly being adapted and arranged to be positioned substantially axially in said duct and comprising a fuel conduit having fuel-receiving and discharging ends, a spray nozzle assembly secured to the discharge end of said conduit, air deflecting means surrounding said nozzle assembly in concentrically spaced relation thereto, a sleeve surrounding said conduit and in bearing contact therewith to permit rotatively angular adjustment of the latter therein, a yoke secured to said sleeve and a bridging member supporting said yoke and sleeve from said air deflector means, and ignition means carried partly by said yoke and partly by said air deflecting means, said conduit being free of said yoke to permit rotatively angular adjustment of said conduit within said sleeve independently of said yoke and air deflector means.

4. A fuel burner of the gun type having an air duct including a blower housing and a blast tube leading from said housing, a firing head assembly in said duct, said assembly including a fuel conduit which extends from a point adjacent the outlet end of said blast tube through the said blower housing to a point outside the latter, said conduit having at its rear or fuel-receiving end a coupling for connecting said conduit to a source of fuel supply, a spray nozzle assembly at the forward end of said conduit, a sleeve surrounding said conduit and in bearing contact therewith to permit rotatively angular adjustment of said conduit therein, said sleeve also extending through the wall of the blower housing, supporting means adjacent the forward end of

said sleeve and in contact with the inner wall of said blast tube, said means fixedly engaging said sleeve to position it substantially axially of said blast tube, and ignition means so carried operatively adjacent the nozzle by said supporting means as to prevent said ignition means from participating in said angular adjustment.

5. A fuel burner as defined in claim 4, wherein in said sleeve is provided, where it passes through the blower housing wall, with means adapted and arranged to engage said wall for preventing rotatively angular movement of said sleeve.

6. A firing head assembly for fuel burners of the gun type having a tubular air blast duct adapted for connection to a blower, said assembly being adapted and arranged to be positioned within said duct substantially axially thereof and comprising a fuel conduit having fuel-receiving and discharging ends, said conduit being of sufficient length to cause its fuel-receiving end to project rearwardly outside said duct when said firing head assembly is properly positioned therein, a flared-tube coupling nipple at the fuel-receiving end of said conduit, the latter being adapted to receive a flared tube and gland nut for connecting said conduit to a fuel supply pipe, a spray nozzle assembly at the discharge end of said conduit, a sleeve surrounding said conduit and in bearing contact therewith to permit rotatively angular adjustment of the latter therein, and a supporting member receiving and fixedly engaging said sleeve to prevent said sleeve from participating in the adjusting movement of said conduit.

7. A firing head assembly for fuel burners as defined in claim 6, wherein said sleeve extends the full distance between said coupling and said nozzle assembly so as to be in endwise abutment with each, whereby longitudinal movement of

20 said conduit with respect to said sleeve is prevented.

5 8. A firing head assembly for fuel burners of the gun type having an air duct including a blower housing and a blast tube leading from said housing, air deflector means stationarily mounted within and engaging the inner periphery of said tube adjacent its nozzle end and having a hub portion extending axially of said tube, and ignition means mounted on said deflector means operatively adjacent the nozzle end of said tube, which firing head assembly comprises nozzle means adapted and arranged to be positioned within said hub portion with freedom for rotative angular adjustment, a sleeve adapted and arranged to be secured thereto and to extend rearwardly therefrom axially of said tube and project through an aperture in a wall of the blower housing, a fuel conduit fitting loosely within said sleeve and projecting rearwardly therefrom, and having provision for rigid connection to said spray nozzle whereby angular turning movement of said fuel conduit within its sleeve will impart corresponding angular movement of said nozzle, and provision at the rearwardly projecting end of said fuel conduit for coupling the same to a fuel supply.
